UNITED STATES PATENT OFFICE

2,442,370

HARMONICA

Jack Messner, Hillside, N. J.

Application August 18, 1944, Serial No. 550,037

6 Claims. (Cl. 84—377)

1

This invention is a new and useful improvement in harmonicas or mouth organs, of which the following is a specification. The invention will be fully understood from the following description read in conjunction with the drawings in which:

Fig. 1 is a side view of the instrument of my invention;

Fig. 2 is an end view of the construction shown in Fig. 1;

Fig. 3 is a top view of the construction shown in Fig. 1;

Fig. 4 is a bottom view of the construction shown in Fig. 1;

Fig. 5 is a section through the construction shown in Fig. 1 on the plane indicated by 5—5;

Fig. 6 is a section through the construction shown in Fig. 1 on the plane indicated by 6—6;

Fig. 7 is a section through the construction shown in Figs. 1—5 on the plane indicated by 7—7 in Fig. 5;

Fig. 8 is a section through the construction shown in Figs. 1—5 on the plane indicated by 8—8 in Fig. 5 and

Fig. 9 is a plan view of one element of the construction shown in Figs. 1, 2, 7 and 8.

The harmonica or mouth organ 1 of my invention comprises body portion 2. This is integral with the mouthpiece 3. A number of play holes 4 for the ingress and egress of air terminate in surface 5. As indicated in Figs. 5 and 8, that portion of these holes adjacent the surface 5 is of substantially tubular form and the play hole gradually flares out, as indicated in Fig. 8, to substantially rectangular cross-section at the point where each play hole terminates in the surface 6 (Fig. 5) forming reed cells 6'.

As shown in Figs. 2, 7 and 8, the body portion 2 is preferably substantially bell-shaped in transverse section. The reed plate 7 of rectangular outline (Fig. 9) rests upon and overlays the surface 6, to bring each pair of reeds 8 over the corresponding reed cell 6'. The reed plate 7 is in turn overlaid by sound cover 9 defining tone openings 11 of circular form in the ends and of slotted form 12 in the sides (Figs. 1 and 6).

The sound cover, reed plate and body portion are assembled and secured merely by passing screws 13 through holes 14 in cover 9, through

2

holes 15 in reed plate 7, and threading same up into holes 16 in body portion 2.

The sound cover and body portion can be made of wood, plastic or any similar material providing a clean smooth surface.

I claim:

1. A harmonica comprising a body portion forming a mouthpiece and defining a number of play holes extending linearly from said mouthpiece, said body portion also forming a substantially flat surface in which said play holes terminate centrally in reed cells, and a reed plate overlaying said flat surface.

2. A harmonica according to claim 1 comprising also a sound cover resting on said reed plate.

3. A harmonica comprising a body portion forming a mouthpiece and defining a number of play holes extending linearly from said mouthpiece, said body portion also forming a substantially flat surface normal to said play holes, in which said play holes terminate centrally in reed cells, and a reed plate overlaying said flat surface.

4. A harmonica according to claim 3 comprising also a sound cover resting on said reed plate.

5. A harmonica comprising a body portion forming a mouthpiece of substantially bell-shaped cross-section defining a number of play holes extending linearly from said mouth-piece, said body portion also forming a substantially flat surface in which said play holes terminate centrally in reed cells, and a reed plate overlaying said flat surface.

6. A harmonica according to claim 5 comprising also a sound cover resting on said reed plate.

JACK MESSNER.
